UNITED STATES PATENT OFFICE.

MARY M. HAMMOND, OF KANSAS CITY, MISSOURI.

TRAY MECHANISM.

1,351,209.

Specification of Letters Patent. Patented Aug. 31, 1920.

Original application filed February 14, 1916, Serial No. 78,283. Divided and this application filed October 31, 1918, Serial No. 260,530. Renewed February 13, 1920. Serial No. 358,403.

To all whom it may concern:

Be it known that I, MARY M. HAMMOND, a citizen of the United States, residing at Kansas City, in the county of Jackson and 5 State of Missouri, have invented a certain new and useful Improvement in Tray Mechanisms, of which the following is a specification.

My invention relates to improvements in 10 tray mechanisms.

It relates particularly to the type of tray mechanisms in which one tray is pivotally connected with another tray so as to be 15 swung from the position mounted thereon to a horizontal position at one side thereof.

One of the objects of my invention is to provide novel means by which the joint between the trays may be made dust and water proof, when the trays are in the superposed position and are subjected to inclement or dusty weather, and which holds the trays from lateral shifting relatively to each other, when they are in the superposed position, thereby eliminating strain on the 25 hinge mechanism which connects the trays.

The novel features of my invention are hereinafter fully described and claimed.

This application is a division of an application filed by me February 14, 1916, 30 having Serial Number 78,283.

In the accompanying drawing which illustrates the preferred embodiment of my invention,

Figure 1 is a perspective view, partly 35 broken away of my improved tray mechanism, the upper tray being shown in the horizontal side position.

Fig. 2 is a vertical sectional view of the same, showing the upper tray swung partly 40 to the horizontal side position and the cover in the open position.

Fig. 3 is a vertical longitudinal sectional view.

Similar reference characters designate 45 similar parts in the different views.

1, 2 and 3 designate respectively the lowermost, intermediate and uppermost trays.

Each tray is connected at its ends with 50 the ends of the adjacent tray by parallel links 4, each pair having its ends pivoted to the adjacent ends of the trays which it connects in a manner such that the trays may be swung from positions superposed one above the other to horizontal upright

positions at one side of the superposed position, as shown in Fig. 1.

The upper edge of each tray is provided, preferably, with a continuous flange 5, which extends all around the upper edge of the tray at the inner side thereof, and which is adapted to fit in the lower side of the tray next above, when the trays are in the superposed position, so as to hold the trays from shifting laterally relatively to each other, and also to prevent access of dirt or moisture at the joint between the trays, when the trays are exposed to inclement or dusty weather. The flanges 5 are sufficiently shallow to permit the trays to freely swing to and from the superposed position, and the upper edge of each tray, at the outer side of the flange 5 is shouldered so as to support the tray next above, with respect to the trays 1 and 2, and to support a cover 6, with respect to the tray 3, to which the cover 6 is hinged at one longitudinal edge, 65 preferably by means of two flexible strips of leather, canvas or other suitable material, designated by 7 and 8 and secured respectively to the inner and outer sides of the tray 3 and cover 6, as is best shown in Fig. 2.

Each tray has a stationary bottom 9 disposed above the lower edge of the tray for the purpose of carrying the articles to be displayed high in the trays so that they may be more efficiently presented to view, and in the case of the trays 2 and 3 to permit the entrance of the flanges 5 of the trays next below.

The tray 1 may be provided with a removable bottom 10, which rests upon two inwardly extending flanges 11 of two upwardly extending plates 12, each having an outwardly turned flange 13, adapted to rest 90 upon the flange 5, as shown in Figs. 2 and 3.

The flanges 11 may be rigidly secured to the removable bottom 10, if desired. The length of the bottom 10 is such that the plates 12 will be held firmly against the inner walls of the tray 1, thereby retaining the plates 12 securely in their proper position.

With the parts assembled as above described, the trays 2 and 3 may be swung 105 from the superposed position above the tray 1 to the upright horizontal side position occupied by tray 3 in Fig. 1. When the

trays are swung to the superposed position, the flanges 5 will seal the trays so as to exclude dust and moisture, and will hold the trays from lateral shifting, thus eliminating strain on the links 4 and their pivots due to such shifting.

I do not limit my invention to the structure shown and described, as modifications, within the scope of the appended claims, 10 may be made without departing from the spirit of my invention.

What I claim is:—

1. In a tray mechanism, two trays adapted to be superposed one upon the other, the lower tray having at its upper edge a continuous flanged portion extending all around said upper edge, the upper tray having side walls which embrace said flanged portion its full length when the trays are superposed one above the other, the flanged portion holding the upper tray against lateral shifting relatively to the lower tray, a removable bottom fitted in the lower tray, and means supported by said flanged portion for supporting the removable bottom.

2. In a tray mechanism, two trays adapted to be superposed one upon the other, the lower tray having extending all

around its upper edge a continuous flanged portion, the upper tray having a raised bottom and side walls which embrace said flanged portion its full length, when the trays are superposed one above the other, the flanged portion holding the upper tray against lateral shifting relatively to the lower tray, a removable bottom fitted in the lower tray, and two plates supporting said removable bottom and having each an outwardly extending flange supported upon said flanged portion.

3. In a tray mechanism, two trays adapted to be superposed one upon the other, the lower tray having extending all around its upper edge a continuous flanged portion, the upper tray having side walls which embrace said flanged portion its full length, two plates, each having an outwardly extending flange resting upon said flanged portion and having each an inwardly extending flange, and a removable bottom supported upon said inwardly extending flanges and adapted to hold said plates tightly against the inner walls of said lower tray.

In testimony whereof I have signed my name to this specification.

MARY M. HAMMOND.
